UNITED STATES PATENT OFFICE.

EARL R. CARLSON, OF MINNEAPOLIS, MINNESOTA.

INTERNAL-COMBUSTION ENGINE.

1,239,081.

Specification of Letters Patent.

Patented Sept. 4, 1917.

Application filed March 22, 1916. Serial No. 85,956.

To all whom it may concern:

Be it known that I, EARL R. CARLSON, a citizen of the United States, residing at Minneapolis, in the county of Hennepin and 5 State of Minnesota, have invented new and useful Improvements in Internal-Combustion Engines, of which the following is a specification.

This invention relates to internal combustion engines of the four cycle type, the engine of this invention being especially designed for use in boats but being also designed for use as a stationary engine or for use in connection with aeroplanes, automobiles and the like, the object of the present invention being to provide means whereby the engine may be efficiently cooled both exteriorly and interiorly by the use of air or air and water combined. A further object 20 of the invention is to provide in connection with an inside air jacket for cooling the piston or pistons and piston rod, air compressing means actuated by the piston rod and operating to force air under pressure 25 through said jacket.

A further object of the invention is to provide in combination with the cylinder or cylinders, one or more air jackets surrounding the same, and air compressing means actuated by the piston and serving to force air under pressure through said air jacket or jackets for the purpose of cooling the cylinders exteriorly of the cylinder walls.

With the above and other objects in view, 35 the invention consists in the novel construction, combination and arrangement of parts, as herein described, illustrated and claimed.

In the accompanying drawings:—

Figure 1 is a longitudinal diametrical section through a double acting engine embodying the present invention.

Fig. 2 is a cross section on the line 2—2 of Fig. 1.

Fig. 3 is a cross section on the line 3—3 of Fig. 1.

Fig. 4 is a fragmentary transverse section on the line 4—4 of Fig. 1.

Fig. 5 is a fragmentary transverse section on the line 5—5 of Fig. 1.

Fig. 6 is a detail perspective view of one of the double packing rings for the inside air jacket.

Fig. 7 is a view similar to Fig. 1 but showing a modified arrangement of certain parts.

Referring to the drawings 1 designates a cylinder, 2 a piston rod working centrally

and longitudinally therein, and 3 pistons fastened to the piston rod 2 and operating at opposite sides of a stationary cylinder head 4 thereby leaving combustion chambers 5 and 6 at opposite sides of the piston head 4.

The piston head 4 is provided with inwardly diverging fuel passages 7 the outer ends of which are both in communication with a fuel inlet valve casing 8, 9 designating the fuel inlet valve which is held normally seated by means of a spring 10 surrounding the valve stem 11 and provided at its outer extremity with an anti-friction roller 12 with which co-operates a valve opening cam 13 having two projections so that in each complete rotation of the cam shaft 14, the valve 9 is opened twice for the purpose of admitting fuel first to one combustion chamber 5 and then to the other combustion chamber 6.

The cylinder head 4 is also provided with exhaust passages 15 controlled by exhaust valves 16 similar in all respects to the valve 9 and the parts associated therewith as just hereinabove described, each exhaust valve 16 being operated by a cam 17 having but one projection or high face and mounted on the same rotary crank shaft 14 with the cam 13. The same rotary cam shaft 14 is provided with cams 18 for periodically opening air inlet valves 19 which control the air inlet passages 20 extending into the combustion chambers 5 and 6 near the opposite faces of the stationary cylinder head 4 as clearly shown in Fig. 1. The cams 18 have only one high face. It will thus be seen that the fuel inlet valve 9 opens twice for each single opening of the valves 16 and 19 and all of said valves are operated at the proper periods by the single rotary cam shaft 14 which is mounted in suitable bearings at one side of the engine.

At each side of the cylinder head 4, the combustion chambers 5 and 6 are surrounded by air jackets 21 which are placed in communication with each other by cooling passages 22 extending through the cylinder head 4, whereby the air from one jacket 21 may be forced through the cylinder head into the other jacket for cooling both ends of the cylinder and also for cooling the cylinder head.

Surrounding the piston rod 2 is an air jacket 23 of tubular form and of greater internal diameter than the external diameter

of the rod 2. The jacket 23 travels or moves with the piston rod and therefore together with the piston rod, works through a central opening in the cylinder head 4. At its opposite ends, the jacket 23 is expanded or enlarged as shown at 24 to cover a greater portion of the area of the adjacent faces of the pistons 3. Each enlarged end portion 24 is shown as flanged at 25 and fastened at 10 26 to the adjacent piston.

To the opposite face of one of the pistons 3 there is secured the expanded or enlarged portions 27 of an air jacket extension 28 which, if desired, may be of less diameter 15 than the jacket 23 just described. Carried by the air jacket extension 28 is an air compressing plunger head 29 which is therefore actuated simultaneously with and by means of the piston rod 2 and serves to compress 20 air in the end portion of the cylinder 1 for the purpose of supplying air under pressure to the outside jackets 21 and the inside jackets 23. A check valve 30 mounted within a threaded and removable valve cage 31 in the 25 end portion of the jacket extension 28 admits a portion of the air under pressure through the jacket extension 28 and through ports 32 in the adjacent piston to the jacket 23, the air continuing its movement through 30 the ports 32 of the other piston 3 at the opposite side of the cylinder head 4 and thence onward through another extension 33 of said air jacket, the last named extension 33 being provided with an expanded or enlarged portion 34 corresponding with the portions 24 of the jacket 23 and secured in the same way and bearing the same relation to the opposite or outer face of the adjacent piston 3.

Air is admitted to the air compressing end 40 of the cylinder 1 through an inlet check valve 35 which is mounted in a removable cage 36 in line with the valve 30. A U-shaped pipe or connection 37 communicates with the air suction chamber 38 between the 45 plunger head 29 and the adjacent head 39 of the cylinder as shown in Fig. 1 and the pipe 37 then communicates by means of a short neck 40 with a manifold 41 the branches 42 of which extend in opposite directions and communicate at their discharge ends at the points 43 with the outside air jackets 21. A check valve 44 contained in a detachable cage 45 is mounted within the connecting neck 40 above referred to and 50 access is had to the valve cage 45 for removing the same by means of a detachable valve plug 46 threaded into an opening in the manifold 41 in line with the cage 45. All of the valves and their cages just referred to 55 are thus removable for the purposes of repair. 48 designates oil inlets for lubricating the interior of the cylinder and the working parts therein.

In order to prevent leakage of compression where the inner jacket 23 slides through

the central cylinder head 4, packing rings 49 are provided, the same being of the split and overlapping extremity type as shown in Fig. 6. Adjacent to each opposite face of the cylinder head 4, two packing rings 49 70 are employed, the same being connected at diametrically opposite points by blocks or yokes 50 which are received in offsets or grooves 51 in the cylinder head 4. This prevents the rings 49 from turning and they 75 are maintained in close contact with the outer surface of the air jacket 23 by means of springs 52 one or both of which may be tensioned by means of adjusting screws 53 inserted radially through the piston head 4 80 from the outside of the cylinder. The yokes 50 are preferably arranged one above the other and in such case, the weight of the upper yoke 50 may be found sufficient to hold the sections of the rings 49 carried thereby 85 in gas-tight contact with the outer surface of the air jacket 23. Annular retaining lips or flanges 54 serve to hold the rings 49 in place and prevent the same from being carried into the combustion chambers of the 90 engine.

Under the arrangement illustrated in Fig. 1, the jacket 23 is provided about centrally of its length or about midway between the pistons 3 with a fuel groove or depression 95 55 whereas under the arrangement shown in Fig. 7, two fuel grooves or dépressions 56 are provided in the jacket 23 and close to or near the expanded or enlarged portions 24 of said air jacket. Under the arrangement shown in Fig. 1, as the left hand piston 3 moves away from the cylinder head 4, air is primarily sucked inwardly through the respective air inlet valve 19 and as soon as the adjacent fuel inlet passage 7 is bridged by the depression or groove 55, the suction of the piston 3 moving away from the piston head 4 causes an inflow of a suitable amount of liquid fuel. In the return movement of the left hand piston 3, the mixture of 100 air and fuel is compressed. The next outward stroke of the piston 3 is the firing stroke, and the final return stroke of the left hand piston 3 toward the cylinder head 4 expels the burned gases through the adjacent exhaust port 15 and outward past the exhaust valve 16. The same operation just described is duplicated at the opposite side of the piston head 4 but, of course, the explosions alternate in the two combustion 110 chambers. In this way the piston rod 2 is actuated in both directions. 115

Under the arrangement shown in Fig. 7, as the left hand piston 3 moves away from the cylinder head 4, fuel is first admitted 125 to the combustion chamber 5 by the suction produced by the piston 3 and after the fuel in the passage 7 is closed or covered by the air jacket 23, the suction produced by the continued movement of the left hand piston 130

3 draws air inwardly through the air inlet valve 19. Therefore the only difference in the operation between Figs. 1 and 2 resides in the fact that, under the arrangement shown in Fig. 1, air is first drawn into the combustion chamber, followed by a charge of fuel, while under the arrangement shown in Fig. 7, the fuel is first drawn into the combustion chamber, followed by the charge 10 of air.

The cylinder 1 may be of any suitable length in accordance with the stroke desired and the body of the cylinder is provided at the opposite extremities thereof with outwardly extending annular flanges 57 to which heads 39 may be bolted or otherwise fastened as shown at 58 or by means of which an additional cylinder 59 may be fastened to the cylinder 1. As stated in a former 15 application filed by me, any number of such cylinders and power units may be coupled together end to end, the piston rod 2 being correspondingly lengthened and the required additional number of pistons 20 3 being mounted thereon in conjunction with the additional stationary cylinder heads 4 and the other parts referred to hereinabove in connection with the description 25 of the single power unit illustrated in Fig. 1. This renders the engine as a whole peculiarly adapted for use in connection with motor boats where there is usually ample room in a fore and aft direction but where there is usually a lack 30 of side room or vertical space. The engine of this invention may practically be mounted under the floor of a vessel so that the presence thereof will not be noticeable and very little useful space will be occupied thereby. 35 40 In such a case it will, of course, be understood that any desired expedient may be brought into use for transmitting the reciprocatory motion of the piston rod 2 into rotary motion for driving the propeller of a motor boat, or any other mechanical element to which rotary motion is to be imparted. The combined power of the impulses obtained in all of the combustion chambers of the connected units is, of course, 45 50 imparted to the common piston rod 2.

Furthermore, it will be understood that the engine is cooled both exteriorly and interiorly and that under the arrangement described and shown, both faces of each 55 piston are cooled throughout the greater amount of their area, in addition to which the cooling air passes through ports in the pistons, as many of such ports being provided as may be found necessary or expedient. While I have described the use 60 of both outside and inside water jackets, it will be understood that in lieu of the outside air jacket, the ordinary jacket may be employed, retaining the inside air jacket 65 for obvious reasons. No additional mech-

anism is required to force air through the outer and inner jackets, with the exception of the air compressing plunger head carried directly by an extension of the inside air jacket, together with the necessary check 70 valves for causing the air to move in the proper direction and preventing back pressure. Supporting rods or projections 60 may be interposed between the piston rod 2 and the air jacket 3 and connected to either 75 one of said parts to prevent possible collapse of the air jacket 3 under the force of the explosions. It will also be seen that by reason of the air and fuel being mixed with 80 in the combustion chamber, there is no waste of the fuel and no occasion for the use of a carbureter.

It will of course be understood that the construction hereinabove described is susceptible of many changes in the form, proportion and minor details of construction which may accordingly be resorted to without departing from the principle or sacrificing any of the advantages of the invention.

Having thus described my invention, I 90 claim:

1. In an internal combustion engine, the combination of a cylinder, an air jacket surrounding said cylinder, a reciprocatory piston, a piston rod, an air jacket surrounding 95 said piston rod and movable therewith, and air compressing means carried by said piston rod jacket and operating to force air into both of said jackets.

2. In an internal combustion engine, the 100 combination of a cylinder, a reciprocatory piston, a piston rod, an air jacket surrounding said piston rod and including a face of said piston, and air compressing means carried by said piston rod jacket and operating 105 to force air into the same.

3. In an internal combustion engine, the combination of a cylinder, a reciprocatory piston, a piston rod, an air jacket surrounding 110 said piston rod and including a face of said piston, and an air compressing plunger head carried by said piston rod jacket and operating to force air into the same, a portion of said cylinder forming an air compressing chamber.

4. In an internal combustion engine, the combination of a cylinder, a reciprocatory piston, a piston rod, an air jacket surrounding 115 said piston rod and including the opposite faces of said piston, and air compressing means carried by the piston rod jacket and operating to force air into said jacket.

5. In an internal combustion engine, the combination of a cylinder, a reciprocatory piston, a piston rod, an air jacket surrounding 120 said piston rod and embodying an expanded portion fastened to the piston and including a portion of one face thereof, and air compressing means including a plunger head carried by said jacket.

6. In an internal combustion engine, the combination of a cylinder, a piston rod, pistons on said rod in spaced relation to each other, a stationary cylinder head between said pistons through which the piston rod passes, an air jacket surrounding said rod and working through the head, and air compressing means including a plunger head actuated by the piston rod for forcing air into the air jacket. 40
7. In an internal combustion engine, the combination of a cylinder, a piston rod, pistons on said rod in spaced relation to each other, a stationary cylinder head between said pistons through which the piston rod passes, an air jacket surrounding said rod and working through the head, said air jacket having its ends expanded to cover the adjacent faces of the pistons, and air compressing means including a plunger head actuated by the piston rod for forcing air into the air jacket. 45
8. In an internal combustion engine, the combination of a cylinder, a piston rod, pistons on said rod in spaced relation to each other, a stationary cylinder head between said pistons through which the piston rod passes, an air jacket surrounding said rod and working through the head, said air jacket having its ends expanded to cover the adjacent faces of the pistons, an extension of said air jacket fastened to the opposite side of one of said pistons, and air compressing means including an air compressing plunger carried by said extension for forcing air into said air jacket and the extension thereof, the last named piston being formed with an air port, and a portion of the cylinder forming an air compressing chamber. 50
9. In an internal combustion engine, the combination of a cylinder, a piston rod, pistons on said rod in spaced relation to each other, a stationary cylinder head between said pistons through which the piston rod passes, air jackets surrounding the cylinder at opposite sides of the cylinder head, and air compressing means including an air compressing plunger actuated by the piston rod, a part of the cylinder forming an air compressing chamber, and the cylinder head being formed with cooling passages through which the air passes from one jacket to the other. 55
10. In an internal combustion engine, the combination of a cylinder, a piston rod, pistons on said rod in spaced relation to each other, a stationary cylinder head between said pistons through which the piston rod passes, an air jacket surrounding said rod and working through the head, air compressing means including a plunger head actuated by the piston rod for forcing air into the air jacket, and packing rings interposed between said air jacket and cylinder head. 60
